MERLE H. DAVIS, OF THE UNITED STATES ARMY, AND DAVID L. WOODBERRY, BOTH OF EDGEWOOD ARSENAL, MARYLAND

BOMB

Application filed February 3, 1928. Serial No. 251,721.

(GRANTED UNDER THE ACT OF MARCH 3, 1883, AS AMENDED APRIL 30, 1928; 370 O. G. 757)

The invention described herein may be manufactured and used by or for the Government for governmental purposes without the payment to us of any royalty thereon.

5 The subject of this invention is a bomb.

In bombing operations against personnel or unprotected positions it is necessary that the explosions of the bomb occur in the air to secure an efficient dispersion of the shell fragments or the chemical, incendiary, or smoke contents of the bomb. To meet this requirement it has been customary to provide a rapid detonating device protruding from the nose of the bomb. While an air burst may thus be 10 secured the bomb is practically on the ground and under the influence of inertia.

According to this invention it is proposed to provide a bomb which is permitted to first strike and penetrate the ground and then be 15 driven rearwardly to a predetermined height above the ground before the bursting charge is set off.

With the foregoing and other objects in view, our invention resides in the novel arrangement and combination of parts and in the details of construction hereinafter described and claimed, it being understood that changes in the precise embodiment of the invention herein disclosed may be made within 20 the scope of what is claimed without departing from the spirit of the invention.

A practical embodiment of the invention is illustrated in the drawings, wherein:

Fig. 1 is a longitudinal sectional view of 25 the bomb constructed in accordance with the invention.

Fig. 2 is an enlarged sectional view of the forward end of the axial tube.

Fig. 3 is an enlarged sectional view of the 30 rear end of the axial tube.

Referring to the drawings by numerals of reference:

The bomb consists of a nose portion 5 and a tail portion 6 united by a frangible connection such as the threads 7. The nose portion 5 is equipped with a delay fuse 8 designed to permit maximum penetration and complete retardation of the bomb before being functioned. The nose portion of the bomb serves 45 as a container for an expelling charge 9 and

is of sufficient capacity to insure propulsion of the tail portion into the air.

The tail portion is provided with a firing pin carrier 10, a delay element 11, a detonator 12 and a booster 13, the explosive elements being encased as a unit for insertion in an axial tube 14 and for retention therein by the carrier 10 when threaded to the tube. This tube is threaded as at 15 in the forward wall of the tail portion and is fitted with a thimble 16 which enters a socket 17 in the rear end of the tail portion.

55 The firing pin carrier 10 slidably mounts a firing pin 18 which is held in the safe position against rearward movement by means of a pin 19 which is sheared when the expelling charge 9 is set off. The firing pin is also held against forward displacement on impact by means of a heavy bolt 20.

Upon impact with the ground, the bomb 70 will penetrate until retarded after which the fuse 8 ignites the expelling charge 9 which breaks the connection 7, drives the firing pin 18 home, and propels the tail portion into the air. The period of the delay in the delay 75 element 11 will be controlled by the nature of the contents of the bomb. For the most effective burst or under special circumstances an air burst of different height may be required depending upon the particular kind 80 of gas in the bomb or whether the contents are incendiary or smoke producing material.

85 We claim:

1. A bomb comprising a tail portion, a nose portion frangibly connected thereto, an expelling charge in the nose portion, a delay fuse in the nose portion, a tube secured to the forward end of the tail portion, and having a socket engagement with the rear end thereof, explosive elements encased as a unit inserted in the tube, a firing pin carrier secured to the tube and retaining the explosive elements, a firing pin slidably mounted in the carrier and available to the expelling charge and means for holding the firing pin against movement towards the expelling charge.

85 2. A bomb comprising a tail portion, a nose portion frangibly connected thereto, an expelling charge in the nose portion, a delay fuse in the nose portion, an axial tube in the 100

tail portion, explosive elements encased as a unit inserted in the tube, a firing pin carrier secured to the tube and retaining the explosive elements, a firing pin slidably mounted in the carrier and available to the expelling charge and means for holding the firing pin against movement towards the expelling charge.

3. A bomb comprising a tail portion, a nose portion frangibly connected thereto, an expelling charge in the nose portion, a delay fuse in the nose portion, a tube secured to the forward end of the tail portion, and having a socket engagement with the rear end thereof and a firing mechanism, including an expelling-charge-actuated firing pin carried by the tube.
